UNITED STATES PATENT OFFICE.

ARMAND COUAILLET, OF ST. OUEN, AND PIERRE DUSSOL, OF PARIS, FRANCE.

MECHANISM FOR VENDING CARDS AND CARTRIDGES FOR TARGET-SHOOTING.

1,371,604.

Specification of Letters Patent. Patented Mar. 15, 1921.

Application filed July 18, 1919. Serial No. 311,841.

To all whom it may concern:

Be it known that we, ARMAND COUAILLET, a citizen of the Republic of France, and a resident of St. Ouen, Seine, France, and 5 PIERRE DUSSOL, a citizen of the Republic of France, and a resident of Paris, Seine, France, have invented new and useful Improvements in Mechanism for Vending Cards and Cartridges for Target-Shooting, 10 which improvements are fully set forth in the following specification.

This invention relates to mechanism for vending target cards and cartridges for target shooting, operated by the introduction 15 of a coin thereinto.

A construction of the vending mechanism according to the invention is illustrated, by way of example, in the accompanying drawing in which—

20 Figure 1 is a perspective view showing the target-shooting apparatus complete with the vending mechanism arranged at *a* in front.

Fig. 2 is a back view of the vending mechanism, on an enlarged scale, all the parts being mounted on the front plate secured to a door *b* visible in Fig. 1, and the casing or box containing the parts of the distributor being removed.

30 Fig. 3 is a side elevation of the mechanism.

Figs. 4 and 5 are detail views.

Figs. 6 to 11 relate to the cartridge magazine and associated parts, and show the 35 same on an enlarged scale.

Fig. 6 is a view in elevation of the magazine.

Fig. 7 is a horizontal section on line 7—7, Fig. 6.

40 Fig. 8 is a bottom view of the distributor element of the magazine, the lower plate *x* being omitted.

Fig. 9 is a section on line 9—9, Fig. 8.

Fig. 10 is a bottom plan view of the complete operating mechanism for the magazine.

Fig. 11 is a bottom plan view of plate *x*.

On the front door *b* of the casing are arranged: at *c*, the slot through which the 50 coin is introduced, at *d* the outlet or discharge opening for the cards delivered, at *e* the cup into which drop the cartridges discharged by the mechanism, and finally at *f*, the operating handle by means of which the 55 parts of the mechanism can be operated as soon as the coin has been introduced.

The coin, after having been introduced at *c*, drops, if the path is free into a chute *c'* and passes at *g* into a recessed portion or pocket of a disk *g'*.

If, when the coin is thus at *g*, the operating handle *f* is turned, the disk *g'* will be rotated, and owing to the presence of the coin, the latter will raise a lever *g''* pivoted about a pin *g'''*. The raising is effected by 60 the action of the coin on an upper rib *h* of the lever *g''*. If there is no coin in the pocket *g*, the end of the lever *g''* will lie in the path of a tenon secured to the disk *g'* and will prevent the said disk from rotating. The coin is therefore necessary in 65 order to allow the disk *g'* to rotate.

On the spindle of the disk *g'* is mounted a cam *i* on the edge of which can travel a roller *i'* mounted at the end of an arm *i'''* 70 rotatable about a pivot *i''*. This arm *i'''* terminates in a knob *j* engaging in the fork *k* secured to an ejector *k'*. When the cam *i* is rotated, the roller *i'* is moved so as to bring about a sliding movement of the ejector *k'* 75 in the direction of the arrow 1 (Fig. 3). The said ejector *k'* pushes forward, during its movement in the direction of the arrow 1, the last card of the pile of target cards contained in the chamber *k''*. This card is 80 expelled through the slot *d* provided in the front plate of the apparatus. The cam *i* has such an outline that, during one portion of its rotation, the card is slowly moved in the direction of the arrow 1, and at the end 85 of the said rotation, the plate *k'* is suddenly brought back to its rear position in order to place it conveniently into the desired position for a new operation. This sudden return of the plate *k'* is effected by a spring 90 *l* (Fig. 3).

At the bottom of the target card compartment *k* there is disposed an upstanding projection or tenon *l'* which is provided upon the free end of the horizontal lower arm *l'''* 100 of a bell-crank lever *l*, whose upper or vertical arm *l''* is adapted to be moved into and out of position to close the coin slot *c* and, hence, acts as a shutter therefor. The said lever *l* is suitably pivoted at *l'* 105 to the adjacent wall of the casing *a*, and is subjected to the action of a spring *12*, which is connected to its upper arm so as to pull the same into slot-closing position. The tenon *l'* is adapted to support the stack of 110 cards contained in the compartment which rest directly upon it and, by reason of their

weight, force it downward against the action of spring 12, with the result that the upper or shutter arm l'' is moved away from the coin slot. When all of the cards 5 have been discharged from the compartment, the spring 12 is enabled to shift the shutter arm l'' into position between the coin slot and the chute c' , with the result that the introduction of further coins into 10 the chute is prevented.

During the rotation imparted to the disk g' in order to produce the working just described, the coin is carried by the disk g' , and when it is at the bottom of the path 15 described by the latter, it drops into the box whence it can be subsequently withdrawn.

Rotation of the disk g' in the direction opposite to the useful direction, is prevented by a ratchet wheel m against which 20 presses the pawl m' .

Rotation of the spindle on which is mounted the disk g' , which, as has been stated, results in the delivery of a card, also results in the falling into the cup e , of two 25 cartridges which can be fired.

One of the characteristic features of the apparatus consists in the presentation of the two cartridges in question. As shown in Fig. 5, these cartridges are connected together, in groups of twos, by means of a 30 paper sleeve o , and at each rotation of the cam i , a block of two cartridges thus constituted, drops into the cup e .

The cartridges, grouped in twos, as stated, 35 are stacked in vertical reservoirs or chambers o' (Fig. 7) arranged radially around an upper plate or cover o'' and a lower distributor o''' , the whole constituting a magazine, as will be understood. The upper 40 plate o'' is provided with slots through which the cartridges can be introduced into chambers o' . In order to prevent the cartridges from shifting and becoming jammed in the chambers o' during transportation, 45 there is arranged in each chamber a stop p , preferably conforming in shape to that of the chamber so as to enable it to slide therein, said stop having at its outer end a threaded stem which projects through a vertical slot o^4 in the chamber and carries a 50 suitable clamping nut adapted to be tightened against the chamber wall after the stop has been pressed down upon the top of the stack of cartridges.

55 The putting in place of the magazine in the apparatus is exceedingly simple: The lower member x''' of the distributor element o''' is provided with a central hollow projection 4 which is adapted to receive a pin or screw p' , the latter thus centering the distributor on the plate p'' carrying the control or operating parts. At the top of the magazine is slidably mounted a curved arm q which terminates in a disk q' which 60 is adapted to fit exactly into an orifice of

the same shape in the plate o'' . The curved arm q has always the tendency to press the disk q' against the plate o'' of the distributor, under the action of a spring q'' , and owing to the engagement of the disk q' in 70 the said orifice in the plate o'' , the magazine is held in place.

If it is desired to remove a magazine, and either to fill it direct with cartridges, or to replace it by a full magazine, it is necessary 75 to move the disk q' away from the plate o'' . To that end, the end r' of a controlling lever r mounted on a pivot r'' , is depressed, the opposite end of the said lever pressing upwardly against the lower end of the rod q . 80 The lever r carries moreover a pivoted arm s provided with a hook s' which can engage under a fixed stop pin s'' mounted behind the front plate a . By acting on the end r' of the lever r , the hook s' is caused to engage the stop s'' . The rod q is therefore moved upwardly away from the plate o'' and held in its new position. It is then possible freely to effect the changing of the magazine or its filling. When this operation is finished, it is sufficient, in order to 85 re-fix the magazine in the apparatus, to allow the rod q to drop back on to the plate o'' by disengaging the pawl or hook s' from the stop s'' . The spring r'' suddenly returns 90 then the disk q' to the hole provided in the plate o'' .

Rotation of the cartridge magazine allows 95 a pair of cartridges to be delivered in the following manner:

The spindle of disk g' (Fig. 2) carries a crank t (Figs. 2 and 10) which is pivoted at one end to a connecting rod t' . The other end of this rod t' is pivoted to a tenon t'' mounted on an arm u adapted to oscillate 105 about the pin p' , said arm carrying a vertical finger u' provided at its extremity with a pawl 2, as shown in dotted lines in Fig. 10. This pawl co-acts with a ratchet x formed around the distributor o''' (see Figs. 4, 6 110 and 8) and thereby effects the rotation of the distributor through a certain angle during its movement in one direction, the pawl moving idly along the ratchet during its return stroke. The finger u' on which pawl 115 2 is pivoted has a to-and-fro sliding movement in a slot 3, (Fig. 10) formed in the plate p'' which is fastened to the casing wall and supports the magazine, such movement being effected by means of the 120 crank t and connecting rod t' . The plate x''' above referred to is centered upon the pin p' by means of its central tubular projection or lug 4 (see Fig. 9) which also centers the distributor element o''' and, hence, 125 the magazine, with relation to the support p'' . The studs y (Figs. 6, 9, 10 and 11) attached to the plate x''' hold the latter stationary by engaging the corresponding holes in plate p'' , (Fig. 10). The plate x''' 130

is cut away at 6 to register with the open lower ends of the successive cartridge chambers o' ; and said plate x''' , moreover, carries upon its upper face in contact with the distributor disk o''' a scraper x'' . An annular recess or groove 8 (Figs. 8 and 9) formed in the part o''' receives the scraper, the depth of said recess being approximately equal to the diameter of a group of two cartridges. Under these conditions when the distributor o''' is turned, the scraper x'' which alines with the slot 6 in plate x''' and with a slot 10 in plate p'' , picks up in the cartridge chamber o' , which turns toward it, the lowermost cartridge couple. The latter is discharged through the open lower end of the chamber and through the registering openings 6 and 10 into the cup e as soon as it is brought into line with the same, the scraper keeping the remaining cartridges piled up in the chamber o' which momentarily alines with said openings.

We claim as our invention:—

1. In a machine for vending target cards and cartridges for target shooting, the combination of separate magazines to contain the cards and cartridges; an ejector associated individually with each magazine; an operating shaft; and means operatively connected to said shaft for producing at substantially the same time a relative movement between both magazines and their associated ejectors, to effect the discharge of articles from both magazines substantially simultaneously.

2. In a machine for vending target cards and cartridges for target shooting, the combination of separate magazines to contain the cards and cartridges, an ejector associated individually with each magazine, one magazine being mounted to rotate relatively to the corresponding ejector, and the other

ejector being mounted to reciprocate in the other magazine; an operating shaft; and connections between said shaft and the rotary magazine and reciprocatory ejector for actuating said magazine and ejector when the shaft is rotated to effect the discharge of articles from both magazines substantially simultaneously.

3. In a machine for vending target cards and cartridges for target shooting, the combination of separate magazines to contain the cards and cartridges, one of which magazines is rotatably mounted; an ejector associated individually with each magazine; an operating shaft; and means operatively connected to said shaft for turning the rotary magazine relatively to its ejector and simultaneously moving the other ejector relatively to the other magazine to effect the discharge of articles from both magazines substantially simultaneously.

4. In a vending machine, the combination of a magazine unit comprising a plurality of vertical chambers and a distributor at the bottom of the magazine having an internal annular recess into which the delivery ends of all of said chambers open and a discharge slot leading from the recess; means for imparting a step-by-step rotary movement to said magazine unit; and a stationary ejector disposed within said recess for discharging one at a time through said slot the articles delivered from the successive chambers into said recess.

In testimony whereof we have signed this specification in the presence of two subscribing witnesses.
